UNITED STATES PATENT OFFICE.

CHARLES BARNES, OF DAYTON, KENTUCKY.

ROTARY FAN.

SPECIFICATION forming part of Letters Patent No. 339,837, dated April 13, 1886.

Application filed June 22, 1885. Serial No. 169,467. (No model.)

To all whom it may concern:

Be it known that I, CHARLES BARNES, a citizen of the United States, and a resident of Dayton, in the county of Campbell and State 5 of Kentucky, have invented certain new and useful Improvements in Rotary Fans, of which the following is a specification.

My invention relates to rotary fans for exhaust and blowing purposes, and especially to 10 that class used in dining-rooms and similar situations for causing a free circulation of air in warm weather and preventing the annoyance from flies. Fans of this class as now constructed are secured to radial arms projecting 15 from a revolving shaft mounted in hangers depending from the ceiling, the shaft being placed longitudinally with the room above the tables. I have observed in places where 20 these fans are used that the air is impelled downward with considerable force upon one side of the room, while the opposite side is comparatively unaffected.

The primary object of my invention is to 25 overcome this defect and insure an equal distribution of the air from the fan upon each side. A further object is a cheap, light fan-blade that can be readily applied.

With these objects in view my invention 30 consists in the arrangement and combination 30 of devices hereinafter described, and particularly pointed out in the claim.

In the accompanying drawings, forming part 35 of the specification, in which like parts are represented by similar reference letters wherever they occur, Figure 1 is a side elevation of a portion of the revolving shaft having one of my improved fans mounted upon it. Fig. 2 is a vertical transverse section taken through line $\alpha\alpha$ of Fig. 1, looking to the left.

40 A represents the shaft, upon which are secured at a suitable distance apart the hubs B,

which are secured upon the shaft by set-screws b. The hub is cast with a hexagonal flange, b'. To the face of the flange b' are secured three arms, C, one edge of the arm being in the 45 same plane as the side of the flange, and the arms being placed opposite the alternate sides, and of course tangential to the path of travel.

The vane D is a tube of canvas or other 50 flexible material stretched around the opposite arms C. It is ornamented or covered with some ornamental paper.

The hubs are adjustable along the shaft by means of the set-screws b, so that they with their 55 arms may be placed any distance apart to provide for the length of the vane, as desired.

I intend to make the hub and arms C separately, so that they will occupy but little space 60 when for shipment, and no skill is required to fit the fan when the hubs and arms are furnished. It is evident that the arms C may also be used in the position they occupy on the flanges for a vane or fan like those in common use; but the form shown is preferable. 65

I am aware it is not new to secure fan-blades to the sides of a square or polygonal shaft, and hence do not claim a fan so constructed.

What I claim is--

In a rotary fan of the character described, 70 the combination, substantially as specified, of the shaft A, hubs B b', secured upon the shaft at suitable distances apart, and the arms C, secured tangentially on the flanges of said 75 hubs, with the webbing D between the opposite arms.

CHAS. BARNES.
